UNITED STATES PATENT OFFICE.

BELVIN T. WILLISTON, OF SOMERVILLE, MASSACHUSETTS, ASSIGNOR TO THE UNITED INJECTOR COMPANY, OF NEW YORK, N. Y., A CORPORATION OF NEW YORK.

SPRING-ADJUSTER.

1,130,050.

Specification of Letters Patent.

Patented Mar. 2, 1915.

Application filed May 23, 1914. Serial No. 840,624.

To all whom it may concern:

Be it known that I, BELVIN T. WILLISTON, a citizen of the United States, and resident of Somerville, in the county of 5 Middlesex and State of Massachusetts, have invented new and useful Improvements in Spring-Adjusters, of which the following is a specification.

My invention relates to spring adjustments, and is addressed particularly to the 10 adjustment of valve springs.

The object of my invention is to provide a spring adjuster which shall always bear accurately on the spring, avoid either torsion or lateral displacement of the spring 15 and thus insure accuracy of adjustment of spring pressure, and which shall occupy less space than spring adjusters heretofore in use.

20 In the drawings hereto annexed which illustrate my invention in that form thereof of which I believe to be the best, Figure 1 is an elevation and part section of a spring adjuster mounted on a valve; Fig. 2 is a 25 side elevation of the spring housing; Fig. 3 is a vertical section of the spring housing on the line 3—3 of Fig. 2, showing the spring saddle and adjusting nut in dotted lines; Fig. 4 is a plan view of the spring 30 saddle; Fig. 5 is a vertical section of the spring saddle on the line 5—5, Fig. 4; Fig. 6 is an end elevation of the spring saddle; Fig. 7 is a plan view of the adjusting nut, partly broken away; and Fig. 8 is a vertical 35 section of the adjusting nut on the line 8—8, Fig. 7.

In Fig. 1 a valve casing is shown at A. The valve within the casing may be any kind of valve which is to be under the control 40 of a spring, such as S, and the casing may therefore be of any type suited to the variety of valve. Upon the valve casing, or secured to it in any suitable manner, there is a spring housing B, which is tubular to accommodate the spring S, externally threaded along the portion B³ which may be longer or shorter, according to the range of spring adjustment to be provided for; the spring housing B may have a flanged base, 45 as B', for the accommodation of holding bolts B². The spring housing B is slotted at opposite sides at B⁴; and at the upper ends of the slots B⁴ there is a saddle-way B⁵, wider than the slots, transversely across 50 the spring housing. The valve spring S

is inserted in the tubular housing B through the open top thereof, so as to bear or exert its influence upon the valve, of whatever nature, in the valve casing A. A saddle C (shown in detail in Figs. 4, 5 and 6) is then 60 inserted laterally through the slots B⁴ and saddle way B⁵. By comparison of Figs. 2 and 6, it will be seen that the crown C' of the saddle C matches the saddle way B⁵ in 65 sectional area, while the laterally and (preferably also) downwardly projecting wings C³ likewise match the slots B⁴ in horizontal dimension. These wings C³ are formed with side bearings C⁴ and step bearings C⁵, and the relative proportions of the spring housing B and saddle C 70 are such that the side-bearings C⁴, when the saddle C is inserted and centered in the spring housing, are about flush with the tops of the threads on the threaded section 75 B³ of the spring housing, and the steps C⁵ project beyond the tops of said threads, in position to be engaged by the lower rim of the adjusting nut D. The spring S will be 80 temporarily compressed (if need be) to permit the insertion of the saddle C into the saddle way B⁵ and slots B⁴. On assembling the parts, the saddle C may be first 85 inserted and the spring S then placed in the spring housing B from below before the housing is attached to the valve casing.

The adjusting nut D is internally threaded to match the threads on the section B³ of the spring housing B, and may have radially projecting handles D'. The lower 90 end of the nut D is bored out to form the saddle-centering surface D², and the lower rim D³ is adapted to bear on the steps C⁵ of the saddle-wings C³. The saddle C being in place (Figs. 1 and 3) the nut D is 95 screwed down on the section B³ of the spring housing B. The saddle-centering surface D² slips into a fairly close fit with the side bearings C⁴ on the saddle wings C³ and the rim D comes to a bearing on the 100 steps C⁵.

Since the steps C⁵ on the saddle-wings C³ are accurately machined and symmetrical with respect to the crown C', on the under side of which the spring S finds its bearing, 105 being centered by the inner boss C², the effort exerted on the spring by the adjusting nut D is symmetrical with respect to the spring. The preferred form here shown, in which the saddle-wings extend down- 110

wardly as well as laterally, still further insures an always accurately centered resultant of effort upon the spring S, because with the bearing surfaces of the steps C⁵ and nut-rim D³ below the point of application of effort on the spring S, the effort on the spring is always an even pull, which holds the saddle C accurately at right angles to the axis of the spring helix, while the centering effort of the surface D² on the side bearings C⁴ insures a constantly central position of the saddle C. Moreover, the engagement of the sides of the slots B⁴ with the wings C³, prevents the saddle C from turning and thus torsionally distorting the spring S. As the diameter of the crown C' of the saddle C is nearly equal to the inside diameter of the tubular housing B, the crown C' finds proper accommodation for its movement in the housing whenever the nut D is turned in either direction for purposes of adjusting the pressure with which the spring S affects the valve under control.

I use the terms "upper", "lower", "downwardly", "vertical" and the like solely as definitive of the positional relationships illustrated in the drawings, and without relation to the posture of the apparatus as a whole with reference to a point of support.

It will be observed that the above described spring adjuster is compact in dimensions and operates wholly within the vertical dimension of the spring housing, requiring no cap or extension above or beyond the spring housing itself.

What I claim and desire to secure by Letters Patent is:

1. The combination, with a spring and a device responsive to the pressure of the spring, of a spring-adjuster comprising a threaded tubular housing for the spring, slotted at opposite sides, a saddle adapted to be mounted on the spring within the housing, said saddle provided with laterally projecting wings extending through the slots in the housing, and an adjusting nut threaded on the housing and bearing on the laterally projecting wings of the saddle, said nut capable of turning in either direction while bearing on the saddle to adjust the position of the saddle.

2. The combination, with a spring and a device responsive to the pressure of the spring, of a spring-adjuster comprising a threaded tubular housing for the spring, slotted at opposite sides, a saddle adapted to be mounted on the spring within the housing, said saddle provided with laterally projecting wings extending through the slots in the housing, said wings having steps for an adjusting nut, and an adjusting nut threaded on the housing and bearing on the said steps, said nut capable of

turning in either direction while bearing on the saddle to adjust the position of the saddle.

3. In a spring adjuster, the combination of a threaded tubular spring housing, slotted at opposite sides, a saddle adapted to be mounted on a spring within the housing, said saddle provided with laterally and downwardly projecting wings extending through the slots in the housing, said wings having steps for an adjusting nut, and the adjusting nut, threaded on the housing and bearing on the said steps.

4. In a spring adjuster, the combination of a threaded tubular spring housing, slotted at opposite sides, a saddle adapted to be mounted on a spring within the housing, said saddle provided with laterally and downwardly projecting wings extending through the slots in the housing, said wings having steps and side-bearings for an adjusting nut, and the adjusting nut, threaded on the housing and bearing on the said steps and side-bearings.

5. In a spring adjuster, the combination of a threaded tubular spring housing, slotted at opposite sides, and provided with a saddle-way at the upper ends of and wider than said slots, a saddle provided with a crown adapted to enter said saddle-way laterally and to be mounted on a spring within the housing, said saddle provided with laterally projecting wings extending through said slots in the housing, said wings having steps for an adjusting nut, and the adjusting nut, threaded on the housing and bearing on the said steps.

6. In a spring adjuster, the combination of a threaded tubular spring housing, slotted at opposite sides, and provided with a saddle-way at the upper ends of and wider than said slots, a saddle provided with a crown adapted to enter said saddle-way laterally and to be mounted on a spring within the housing, said saddle provided with laterally projecting wings extending through said slots in the housing, said wings having steps and side-bearings for an adjusting nut, and the adjusting nut, threaded on the housing and bearing on the said steps and side-bearings.

7. In a spring adjuster, the combination of a threaded tubular spring housing, slotted at opposite sides, and provided with a saddle-way at the upper ends of and wider than said slots, a saddle provided with a crown adapted to enter said saddle-way laterally and to be mounted on a spring within the housing, said saddle provided with laterally and downwardly projecting wings extending through said slots in the housing, said wings having steps for an adjusting nut, and the adjusting nut, threaded on the housing and bearing on the said steps.

8. In a spring adjuster, the combination

of a threaded tubular spring housing, slotted at opposite sides, and provided with a saddle-way at the upper ends of and wider than said slots, a saddle provided with a 5 crown adapted to enter said saddle-way laterally and to be mounted on a spring within the housing, said saddle provided with laterally and downwardly projecting wings extending through said slots in the housing, 10 said wings having steps and side-bearings

for an adjusting nut, and the adjusting nut, threaded on the housing and bearing on the said steps and side-bearings.

Signed by me at Boston, Massachusetts, this 21st day of May 1914.

BELVIN T. WILLISTON.
